United States Patent Office.

DANIEL W. AYRES, OF SHELDON, ILLINOIS.

Letters Patent No. 79,049, dated June 23, 1868.

IMPROVED DEVICE FOR GRINDING TOOLS.

The Schedule referred to in these Letters Patent and making part of the same.

TO ALL WHOM IT MAY CONCERN:

Be it known that I, DANIEL W. AYRES, of Sheldon, in the county of Iroquois, and State of Illinois, have invented a new and improved Portable Device for Grinding Tools; and I do hereby declare that the following is a full, clear, and exact description thereof, which will enable those skilled in the art to make and use the same, reference being had to the accompanying drawings, forming part of this specification.

This invention relates to a new and improved portable device for grinding tools of various kinds, but more especially for grinding the knives of the sickles of grain and grass-harvesters.

In the accompanying sheet of drawings—

Figures 1 and 2 are elevations of my invention.

Similar letters of reference indicate corresponding parts.

A represents a stock or frame, which may be constructed similar to a bit-stock, and having a shaft fitted in it at right angles, on which a driving-wheel, B, is placed, having two sets of teeth, *a b*, one set, *a*, being on the periphery of the wheel, and parallel with the axis of the same, and the other set, *b*, being on a bevelled surface at one side of the wheel, near its periphery.

The teeth *a* gear into a pinion on a shaft, which has grindstone or emery-wheel C upon its outer end, and the bevel-teeth *b* gear into a bevel-pinion, *c*, on a shaft, *d*, in the stock A, the shaft being at right angles with the axis of the driving-wheel B.

On the outer end of the shaft *d* there is secured a conical grindstone or emery-wheel, D, shown in both figures.

The driving-wheel B has a handle, *e*, attached, for the convenience of turning it.

Either the circular grinding-wheel C or the conical grinding-wheel D may be used, as occasion or convenience may require.

This is quite a portable affair, and may be used for grinding the knives of harvesters, without removing the sickle from the machine, the former being rendered inoperative by throwing the driving-mechanism out of gear, and then applying the grinding-wheel to the knives, the stock being held like an ordinary bit-stock, and the wheel B turned by hand.

The implement may be carried into the field, kept in the tool-box of the machine, and used from time to time, as occasion may require.

In other cases, the stock A may be secured on a table or bench by screws, or any suitable clamp, and the tool applied to either grinding-wheel, C or D; the latter being preferred for grinding the knives of harvesters for sickles.

The relative size of the gearing should be such as to give the proper speed to the grinding-wheels, which speed should be considerably greater than that of the driving-wheel B.

I claim as new, and desire to secure by Letters Patent—

An implement for grinding or sharpening tools, composed of a stock, gearing and grinding-wheels, one or more, arranged to operate in the manner substantially as shown and described.
